(57) **CLAIM**

The ornamental design for a twenty-sided die, as shown and described.

DESCRIPTION

FIG. 1 is a side view of the twenty-sided die showing my new design;

FIG. 2 is another side view thereof;

FIG. 3 is another side view thereof;

FIG. 4 is another side view thereof;

FIG. 5 is another side view thereof;

FIG. 6 is a top view thereof; and,

FIG. 7 is a bottom view thereof.

The arrows shown in dashed lines on each face of the hand thrown die illustrate a directional arrow which can also be reversed, or non-existent, and form no part of the claimed invention.
